UNITED STATES PATENT OFFICE.

HAROLD WALL, OF SALT LAKE CITY, UTAH.

AERATOR FOR FLOTATION ORE SEPARATORS.

Application filed July 28, 1925. Serial No. 46,558.

This invention relates to aerators suitable for use, for example, in flotation ore separators, wherein mineral particles are separated from the rock or gangue of the comminuted ore by causing air bubbles to rise through a mixture of pulverized ore or pulp, water, oil and acid, the rising air bubbles carrying upward the mineral particles and forming a froth, retaining the mineral particles, at the top of the mixture.

Heretofore the common practice has been to form the bubbles by forcing air through a mat of heavy textile fabric lying upon an inclined pan or bed near the bottom of the separator cell while the pulp mixture flows through the cell over the mat, to cause the air to be extensively distributed under the pulp and to rise therethrough in the form of small bubbles.

An undesirable feature of the fabric mat is that the oil and acid of the pulp mixture causes it rapidly to deteriorate and it frequently becomes clogged, especially with oxide of iron from the pulp, and requires to be beaten to free it of the lodged material so that it will function uniformly throughout its extent. The fabric mat also frequently becomes broken or pervious to the pulp, with the result that when the air is shut off the pulp mixture flows into the air line, clogging the latter with sediment, and requiring much time and labor to clear it for further operation.

My chief objects are to provide an improved aerator having great durability, especially under conditions of use in a flotation ore separator, to provide an aerator adapted effectively to prevent the flow of a pulp mixture or the like into the air pipe or pipes when the air pressure is cut off, to provide for a uniform distribution of the air substantially throughout the extent of the aerator, and to provide an aerator adapted for long continued service without difficult or expensive treatment to keep it in serviceable condition.

Of the accompanying drawings,

Fig. 1 is a longitudinal vertical section of an ore separator cell, and my improved aerator in place therein.

Fig. 2 is a fragmentary perspective view of my aerator, part being broken away for clearness of illustration.

Fig. 3 is a section on line 3—3 of Fig. 2, on a larger scale.

Fig. 4 is a section similar to Fig. 3 of a modified form of aerator.

Fig. 5 is a section on line 5—5 of Fig. 3.

Fig. 6 is a vertical section of a modification.

Referring to the drawings, 10 is a rectangular ore separator cell provided with the usual spillway 11, pulp-inlet chute 12, liquid-level control pipe 13, and gangue outlet conduit 14. My improved aerator, generally designated 15, is mounted above the bottom of the cell just below the pulp inlet 12 upon suitable bracket supports such as the one shown at 16, said supports being inclined downwardly from said pulp inlet toward the opposite end of the cell above the gangue outlet 14. For supplying air locally to the aerator, air pipes or hoses 17, 17 connect with the same from below, said pipes leading from an air manifold 18 provided with a shut-off valve 18^a and adapted to receive compressed air from a centrifugal blower 19.

The aerator 15 comprises a flat, relatively thick slab or bed member of hard rubber 20, and a rubber mat 21 mounted thereon, said mat being formed with a multiplicity of small perforations 27, 27 substantially throughout large zones thereof defined by imperforate marginal zones 22, 22 and 85 transverse imperforate zones 23, 23, and being secured to the hard rubber slab or bed 20 by vulcanization throughout the said imperforate zones, so that air forced through one of the pipes 17 into the space between 90 the bed and one of the perforate zones can escape only through the perforations of that zone.

Substantially at the middle of each perforate zone the mat 21 is formed with an integral, upstanding, hollow cap 24, which covers the upper end of a tubular metal nipple 25, molded into the bed 20 and projecting from each face of the latter, the lower end of said nipple being connected with the 100 respective pipe 17. At the base of each cap 24 the sheet 21 is formed with an imperforate, concentric, rather extensive, valvular zone 26, which is preferably sufficiently thick adjacent the cap to prevent the sheet 105 21 from excessively hinging or flexing at the base of the cap when the latter is urged upward by incoming air from the nipple 25. The valvular zone 26 is adapted to seal against the bed 20 when the air supply is 110

stopped, substantially to prevent a return flow of pulp mixture. The cap 24 is formed with internal, vertical ribs 24^a, 24^a adapted to bear against the nipple to prevent undue inward flexing of the vertical wall of the cap under the force of the pulp mixture when the air is cut off. The upper or end wall 24^b of the cap is flexible and is adapted to be lifted by and to permit the passage of compressed air forced upward through the nipple and to be pressed downward and to close the mouth of the nipple to prevent a return flow of air when the air supply valve 18^a is closed.

15 The perforations 27 are arranged in parallel rows longitudinally and transversely of the aerator, each perforation being frusto-conical in shape with its small end opening onto the upper face of the sheet 21.

20 Each perforation is connected with adjoining perforations by longitudinal grooves such as the one designated 28 and transverse grooves 29, 29, in the lower face of the mat, Fig. 3, said grooves being adapted to distribute air evenly from the inlet pipes 17 to the various perforations notwithstanding the fact that portions of the sheet 21 may be pressed tightly against the supporting slab 20 by the overlying pulp. My invention, however, is not wholly limited to the presence of such grooves. The grooves 28, 29 do not intersect the cavities within the respective caps 24, the lower face of the zone 26 being smooth and flat and adapted to act as a self-seating valve, except as its operation may be affected by grit, to prevent return flow of fluid into the nipple 25 when the supply of compressed air is stopped.

25 The aerator is preferably constructed of an abrasion resisting rubber compound and one of such character as not to be affected by oil, acid, or oxidized iron, so that a relatively long period of usefulness is obtained.

30 In the operation of my apparatus, the pulp 30 being caused to flow through the cell 10 in the usual manner, air is forced through the nipples 25 into the spaces between the perforated zones of the mat and the bed member 20, the hollow caps 24 being lifted by the air pressure, against the weight of the overlying pulp, and the air escapes through the perforations 27 of the mat. The grooves 28, 29 insure a substantially uniform distribution of the air to the various perforations even though the air pressure is not sufficient to raise the perforated zones of the mat from the bed 20 throughout any or all of their extent.

35 The conical shape of the perforations 27 results in the forming of very small air bubbles and also avoids clogging of the perforations. The walls of the perforations being elastic, the perforations vary in size with variations of the air pressure, enlarging as the air pressure increases, admitting

air to the pulp mixture with a spray effect, which is contributed to by the resilience of the elastic aperture walls, with the result that very fine bubbles are produced both when the air is forced rapidly, with high pressure, through the enlarged holes and when the air under less pressure is forced more slowly through the holes with the latter in a less dilated condition.

70 The weight of the pulp mixture within the cell presses the base 26 of the cap and other parts of the mat upon the supporting slab 20 when the air pressure within the nipple 25 is less than sufficient to support the column of pulp mixture, as in case of air leakage or in case of an increase in the height of the column, a seal thus being effected between the mat and the bed member to prevent flow of pulp into the air line. Under the same conditions also the upper or end wall 24^b of the cap 24 is pressed downward by the pressure of the pulp mixture and closes the mouth of the nipple against return flow of air, even though the 75 valvular zone 26 should fail to function perfectly.

75 It will be observed that since the nipple 25 rises to a substantial height above the bed 20, none of the fluid containing the gritty pulp can enter the nipple until all of the air external to the nipple within the cap has been forced back thereinto, and that if such return flow of air be prevented, either by described closing of the mouth of the nipple or by air pressure within the nipple, the return flow of fluid is limited by an 80 overlying layer of entrapped air.

85 Such an overlying layer of entrapped air may be provided by the use of the upwardly projecting nipple 25 and the enclosing cap 24 without the aid of the sealing effect of the cap's end wall 24^b or the valvular zone 26, and if the volume of entrapped air within the nipple and its supply connections be 90 made sufficiently small, as by positioning shut-off valves close to the nipple, as in the modification shown in Fig. 6, the increase of air pressure within the nipple incident to forcing the external air back 95 thereinto will be so great as not to be brought about by even a very great increase of head in the liquid, as in filling the cell at the beginning of operation. This will 100 readily be understood upon consideration of the fact that if the entrapped air were of equal volume on the two sides of the nipple's mouth, and were at atmospheric pressure, the forcing of the external air back 105 into the nipple would increase the pressure therein to two atmospheres, so that the liquid would be subjected to a pressure differential of one atmosphere, which is sufficient 110 to support a column of the pulp mixture 115 many feet in height.

120 Such high pressure within the nipple is 125

of course not relied upon when the valvular action of the cap's end wall 24^b is employed, since the valvular action calls for greater fluid pressure upon the liquid side than upon the air side of the valve, but in either case the rise of liquid toward the mouth of the nipple is limited by an overlying layer of entrapped air.

When the shut-off valves are provided closely adjacent the nipple 25, as shown in Fig. 6, where the valves are designated 18^b, 18^a, they are provided with actuating means adapted to be operated from the exterior of the cell. The means here shown comprises a valve-actuating rod 35 entering the cell through a suitable gland 36 and having blocks 37, 37 slidably mounted thereon and having stud-and-slot connection with the respective valve levers 38, 38. In order that all of the valves may be firmly closed by the same rod each block is mounted to yield by sliding upon the rod and is backed on each side by a compression spring 39, mounted upon the rod and seating against a collar 40 secured on the rod, so that if one valve seats slightly before another, because of inequalities of construction or adjustment, the rod may nevertheless be moved somewhat farther, to seat the other valves.

In the modification shown in Fig. 4, the sheet 21^a, upon the supporting bed 20, is formed with perforations in the shape of slots 31, 31 disposed at right angles to each other and having inclined side and end walls to form relatively small elongated apertures in the top surface of the bed member. The slots 31 are adapted to spray fine sheets of air into the pulp mass, said sheets intersecting over each other so as more intimately to mix with and agitate said mass.

In my aerator as described I prefer to employ a bed of plane form, as the rubber mat functions better therewith, but my invention is not wholly limited thereto.

The mat may readily be freed from solid matter lodged in its perforations by flexing and stretching of the mat.

Various modifications may be resorted to without departing from the scope of my invention as defined in the appended claims.

I claim:

1. The combination, with a flotation ore-separator cell, of an aerator therein, said aerator comprising air distributing means and means for conducting air thereto, the last said means comprising a device adapted to prevent a return flow of liquid by opposing to the liquid an overlying layer of entrapped air.

2. An aerator comprising a bed member, an air-supply nipple projecting upward therefrom, and a perforate mat lying upon said bed member and formed with an imperforate cap portion surrounding said nipple.

3. An aerator as defined in claim 2 in which the cap portion of the mat is adapted to act as a valve against the mouth of the nipple.

4. An aerator as defined in claim 2 in which the cap portion of the mat is adapted to seal against the bed member about the base of the nipple.

5. An aerator as defined in claim 2 in which the cap portion of the mat is adapted to seal against the mouth of the nipple and also against the bed member about the base of the nipple.

6. An aerator comprising a bed member, an air conduit having a discharge orifice in communication with the upper face of said bed member, and a perforate mat lying upon said bed member and having an imperforate portion adapted to act as a valve to permit air to pass from said conduit into the space between said bed member and the perforate portion of the mat but to prevent a return flow of fluid into said conduit.

7. The combination, with a flotation ore-separator cell, of an aerator comprising a bed member, an air-supply conduit communicating with the upper face of the said bed member, and a perforate rubber mat lying upon said bed member and formed with air-distributing channels in its face adjacent the bed member.

8. A flotation ore-separator comprising a container for the ore mixture and an aerator therein, said aerator comprising a perforate rubber mat, a bed member underlying the mat and an air conduit leading to the space between the two, said mat having an imperforate portion and said conduit having a terminal portion projecting upward from the face of said bed member and adapted to be sealed by the imperforate portion of the mat in the manner of a valve to prevent a return flow of liquid into said conduit when the current of air in the latter is stopped.

9. An aerator comprising a bed member, perforate rubber matting lying thereon and sealed thereto in zones defining segregated areas of the perforate matting, and individual pipes adapted to conduct air into the respective spaces between the said areas and the bed member, the said bed member underlying the said matting and being formed with a substantially non-channelled upper face adapted directly to support the matting substantially without downward stretching of any part thereof by a preponderating pressure of the ore mixture upon its upper surface, and the pipes being of such small cross-section as to provide a substantial equalizing effect upon the relative volumes of air passing therethrough.

10. The combination, with a flotation ore-separator cell, of an aerator therein, said aerator comprising a bed member, a per-

fomated rubber mat lying thereon, and means for forcing air between the two, the bed member and the mat being so constructed that the mat will seal against the bed member when the current of air is stopped and prevent the overlying material from flowing backward through the perforations of the mat.

11. An aerator comprising a bed member, 10 a perforated rubber mat lying thereon, said

mat being formed with distributing channels in its face adjacent the bed member, the mat and the bed member being adapted to coact as a valve in sealing the lower mouths of the perforations and distributing channels to prevent a return flow between the bed member and the mat. 15

In witness whereof I have hereunto set my hand this 6th day of July, 1925.

HAROLD WALL.
